UNITED STATES PATENT OFFICE.

EUSTACE CREEES AND CHARLES S. COURT, OF PROVIDENCE, RHODE ISLAND,
ASSIGNORS TO THE WATSON & NEWELL COMPANY, INCORPORATED, OF
ATTLEBOROUGH, MASSACHUSETTS.

DESIGN FOR A SPOON-HANDLE.

SPECIFICATION forming part of Design No. 25,505, dated May 19, 1896.

Application filed March 24, 1896. Serial No. 584,695. Term of patent 7 years.

To all whom it may concern:

Be it known that we, EUSTACE CREEES and CHARLES S. COURT, citizens of the United States, residing at Providence, in the county of Providence and State of Rhode Island, have invented and produced a new and original Design for Handles for Spoons, Forks, and Similar Articles; and we hereby declare that the following is a full, clear, and exact description of the same, reference being had to the accompanying drawing, forming part of this specification.

The drawing is a front view of our newly-designed handle, showing the same in connection with the bowl of a spoon in solid lines and the conventional outlines of a fork in broken lines.

The leading feature of our design consists in the peculiar and novel outline and ornamentation of the handle, the stem or lower part of the handle being formed of two slightly curved raised beads spreading outward at the upper and lower ends and terminating in inwardly-extending foliations, the upper or escutcheon part of the handle being formed of two long scrolls foliated at the upper part and inclosing an elongated bulb having a deeply-scalloped margin, the whole surmounted by three scrolls, giving to the upper end of the handle a contracted terminal.

The shank or lower part 3 of the handle has on each side the raised bead 4, the lower ends 5 of which curve outward and terminate in the scroll 6. On the inner sides of the beads 4 is the narrow marginal line 7, which terminates at the lower end of the handle into the foliation 8. The upper ends of the beads

4 terminate in the foliations 9, which extend toward the center of this the widest part of the stem of the handle. The small pyramidal ornament 10 extends from the foliations 9 in the center of the handle. From the foliations 9 extend upward the long scrolls 11. First curving inward and contracting the width of the handle, they gradually curve outward, and at their upper ends, abruptly curving inward, they terminate in the foliations 12, which extend over the plate or escutcheon part 13 of the handle and are surmounted by the scrolls 14 and 15, forming the raised terminal of the handle. The escutcheon part 13 of the handle between the long scrolls 11 is ornamented by the convex bulb 16, having the deeply-scalloped margin 17, surmounted by a terminal leaf final. The simple curved outline of the stem, uniting at its widest part with the scrolls ornamenting the margins of the plate or escutcheon of the handle, presents to the eye the appearance of the growth or gradual evolution of the bulb 16 and ornamentation of the plate from the stem.

Having thus described our newly-designed handle, we claim as new and desire to secure by Letters Patent—

The design for the handle of a spoon, fork or similar article, substantially as herein shown and described.

In witness whereof we have hereunto set our hands.

EUSTACE CREEES.
CHAS. S. COURT.
